UNITED STATES PATENT OFFICE.

DAVID STEWART, OF PITTSBURG, PENNSYLVANIA.

TOMBSTONE.

SPECIFICATION forming part of Letters Patent No. 734,770, dated July 28, 1903.

Application filed October 4, 1902. Serial No. 125,877. (No model.)

To all whom it may concern:

Be it known that I, DAVID STEWART, a citizen of the United States, residing at Pittsburgh, in the county of Allegheny and State of Pennsylvania, have invented a new and useful Improvement in Tombstones, of which improvement the following is a specification.

My invention relates to an improvement in tombstones. It has for its object to provide a tombstone which will be durable, effective, and ornamental and one that will be readily and expeditiously set up and one which will be easy and inexpensive to produce.

Figure 1 is a front elevation view. Fig. 2 is a vertical sectional view. Fig. 3 is a transverse sectional view taken on the line 3-3 of Fig. 2, and Fig. 4 is a detail perspective view of the locking-post.

In the drawings, 1 designates the tombstone proper, which may be of glass, porcelain, or any other suitable material and may be appropriately decorated and inscribed. It is provided with a central aperture 2, extending partially through the stone, which aperture 2 has grooves or ways 3 formed in its sides. At the top of the aperture 2 the stone is formed with recesses 4, adapted to receive projecting lugs 5 of a hollow metallic post 6. The post 6 is hollow and is secured in the ground, preferably by packing the earth around it and partially filling it and tamping the dirt down. It is provided on its upper end with lugs 5, which are adapted to slide in the grooves 3 of the stone when the latter is slipped over the post.

It will be readily seen that after the post 6 has been secured in the ground in the manner

described the tombstone may be slipped over it and the lugs 5 will ride down the grooves 3 until the stone rests on top of the post 6, when the stone may be given a quarter-turn and the lugs 5 will ride into the recesses 4, as clearly shown in Fig. 3, and thus lock the stone on the post 6 against longitudinal movement.

I do not wish to limit myself to the exact details of construction and operation herein set forth, as I may make various changes in the same within the scope of my claims and without departing from the spirit of my invention.

Having thus described my invention, what I claim as new is—

1. The combination with a tombstone having a central aperture provided with grooves, of a post fitting in the aperture, lugs on the post adapted to be received by the grooves, and means for locking the post in the stone, substantially as described.

2. The combination with a tombstone having a central aperture provided with grooves and recesses formed in the upper ends of the grooves, of a post fitting in the aperture, lugs formed on the post and adapted to be received by the grooves, and the stone adapted to be turned to cause the lugs to ride in the recesses and lock the stone on the post, substantially as described.

In witness whereof I have hereunto signed my name in the presence of two subscribing witnesses:

DAVID STEWART.

In presence of—

FRED. O. HENZE,
M. HUNTER.
